United States Patent Office

Des. 178,542
Patented Aug. 14, 1956

178,542

STATION WAGON

David E. Scott, Royal Oak, Mich., assignor to Chrysler Corporation, Highland Park, Mich., a corporation of Delaware

Application December 19, 1955, Serial No. 39,368

Term of patent 7 years

(Cl. D14—3)

FIG. 1

FIG. 2

Fig. 1.

Fig. 4.

Fig. 1 is a perspective view of the front of a station wagon showing my new design;

Fig. 2 is a side elevational view of a station wagon shown in Fig. 1;

Fig. 3 is a front elevational view of a station wagon shown in Fig. 1; and

Fig. 4 is a rear elevational view of a station wagon shown in Fig. 1.

The dominant features of my design reside in the portions shown in full lines.

I claim:

The ornamental design for a station wagon, substantially as shown and described.
